FILM INSPECTING MACHINE

Robert F. Menary, Northbrook, and Joseph R. Sobieraj,
Schiller Park, Ill., assignors to Paulmar Inc., Chicago,
Ill., a corporation of Illinois

Application March 5, 1959, Serial No. 54,861

Term of patent 14 years

(Cl. D61—1)

Fig. 1 is a perspective view of a film inspecting machine embodying our new design;

Fig. 2 is a front elevational view of the machine; and
Fig. 3 is a top plan view thereof.

The back of the machine is plain and unornamented, and the end of the machine not shown is like the end illustrated in Fig. 1.

The broken line showing of representative reels in Figs. 1 and 2 is for illustrative purposes only.

We claim:

The ornamental design for a film inspecting machine, substantially as shown and described.
